(57) **CLAIM**

The ornamental design for a microphone and speaker capsule for cellular headsets, as shown and described.

DESCRIPTION

FIG. 1 is a perspective view of the microphone and speaker capsule of the present design;

FIG. 2 is a front view of the microphone and speaker capsule of FIG. 1;

FIG. 3 is a back view of the microphone and speaker capsule of FIG. 1;

FIG. 4 is a left side view of the microphone and speaker capsule of FIG. 1, the right side view being identical thereto;

FIG. 5 is a bottom view of the microphone and speaker capsule of FIG. 1; and,

FIG. 6 is a top view of the microphone and speaker capsule of FIG. 1.

The broken lines are for illustrative purposes only and form no part of the claimed design.
